GEORGE S. EMERICK, OF NAZARETH, PENNSYLVANIA, ASSIGNOR, BY MESNE ASSIGNMENTS, TO J. WALTER KEELY, OF PHILADELPHIA, PENNSYLVANIA.

GRINDING-MILL.

1,171,933.

Specification of Letters Patent.

Patented Feb. 15, 1916.

Application filed June 6, 1912, Serial No. 702,042. Renewed May 14, 1914. Serial No. 838,618.

To all whom it may concern:

Be it known that I, GEORGE S. EMERICK, a citizen of the United States, residing at Nazareth, in the county of Northampton and State of Pennsylvania, have invented certain new and useful Improvements in Grinding-Mills, of which the following is a specification.

This invention relates to grinding or pulverizing mills.

The object of the invention is to increase the capacity of grinding mills now in use by the provision of a mill in which is employed a plurality of grinding rings, located one 15 within another, and supported and operated so that an exterior grinding face of one ring may coöperate with an interior grinding face of another ring to effect the grinding operation.

20 A further object of the invention is to construct the parts so that the material to be ground may pass from one grinding ring to another; and a further object of the invention is to employ a plow in combination 25 with a moving grinding ring to divert the material being ground from one position in the ring to another position therein to increase the efficiency of the mill.

20 The invention also includes various novel 30 features of construction and combinations of parts which will be hereinafter fully described and claimed.

In the accompanying drawings, illustrating 35 my invention: Figure 1, is a side elevation, partly in section, on line 1—1 of Fig. 2, illustrating my improved grinding machine. Fig. 2, is a vertical section, on line 2—2 of Fig. 1. Fig. 3, is a vertical section, on line 3—3 of Fig. 2. Fig. 4, is a horizontal section through one of the grinding rings and adjuncts, showing the feed channels, and the plows with their coöperating parts.

40 Referring to the drawings, 4 designates the base of the machine which may be constructed of concrete or other suitable material. This base is provided with bottom, side and end walls forming a chamber to receive the ground material.

45 Secured to the side walls of the base 4 are 50 plates 5 which are provided with bearings 6 through and between which the main shaft 7 of the machine extends.

Formed on or secured to the shaft 7 between the bearings 6 is a grinding roller 8 55 having a hardened outer portion 9 secured to

the body thereof. Surrounding the roller 8 is a grinding ring 10 having an interior diameter greater than the exterior diameter of the roller 8, surrounding the grinding ring 10 is a grinding ring 11 having an interior diameter greater than the exterior diameter of the ring 10, and surrounding the grinding ring 11 is a grinding ring 12 having an interior diameter greater than the exterior diameter of the ring 11, as 60 shown. The ring 10 rests upon the top of the roller 8 and the ring 12, rests upon the top of the ring 11, providing a space above the lower portion of the inner face of each grinding ring, as shown, into which the material to be ground may be discharged to be received upon the inner face of each grinding ring, the grinding operation taking place within the grinding rings, as will be herein-after explained.

65 The material to be ground may be fed to and upon the inner faces of the grinding rings 10, 11 and 12 through inwardly-extending spouts 13, 14 and 15, respectively, extending inwardly from and communicating 70 with the lower portions of suitably supported feed hoppers 16.

75 The ring 11 is made wider than the ring 10 and the ring 12 is made wider than the ring 11, so that the material being ground 80 may fall from the edges of the ring 10 to the inner face of the ring 11, from the edges of the ring 11 to the inner face of the ring 12 and finally from the edges of the ring 12 to the receptacle for the ground material.

85 The inner face of each grinding ring 10, 11 and 12 is made concave in cross section and the outer face of each ring and the outer face of the grinding roller 8 is made convex in cross section, the outer faces of the roller 90 and grinding rings conforming in cross section to the inner faces of the rings surrounding the same, as shown. This construction, it will be understood causes the rings to run centrally upon each other and upon the roller 100 8 when the same are rotated.

95 The shaft 7 is rotatably mounted in split 105 collars 17 which are supported by and mounted to turn in the bearings 6 about the shaft 7. Extending upwardly from the split collar 17 in each bearing 6 is a frame 18, comprising a pair of parallel bars 19 extending from the inner end of the collar 17, a pair of parallel bars 20 extending from the outer end of the collar 17 and a head or top 110

member secured to the upper ends of the bars 19 and 20. These bars 19 and 20 form vertical guideways to which is fitted a pair of bearings 22, one bearing being carried by 5 one frame 18 and the other bearing being carried by the other frame 18. Extending between and mounted in the bearings 22 is a shaft 23 carrying a presser roller 24 arranged above and engaging the top of the 10 outer grinding ring 12, the face of the roller 24 being made concave in cross section to conform to the outer face of the ring 12.

The shaft 23 is bodily movable toward and 15 from the shaft 7 in parallel relation thereto by the movement of the bearings 22 within their guideway in the frames 18. The bearings 22 and therewith the shaft 23 and roller 24 are forced downward by the action of 20 springs 25 to cause the presser roller 24 to force the grinding rings 10, 11 and 12 into engagement with each other and into engagement with the grinding roller 8 with the 25 desired crushing pressure during the grinding operation, the springs 25 permitting the roller 24 to yield upwardly as the material being ground passes between the rollers 8 and 24. The bottoms of the springs 25 bear upon the tops of the bearings 22 and the tops of the springs 25 are provided with caps 26 30 which are engaged by the lower ends of suitable adjusting screws 27 which are screwed into and through the heads 21, whereby, by adjusting the screws 27, the pressure of the springs 25 and therefore the pressure of the 35 roller 24 may be nicely regulated to vary the crushing pressure upon the grinding rings to meet various requirements.

Each frame 18 is movable about the axis of the shaft 7 and each frame is maintained 40 normally in the upright position shown by two vertically arranged springs 29 having their lower ends bearing upon the underlying plate 5 and their upper ends bearing against the bottoms of oppositely-disposed 45 arms 30 projecting laterally from the frame 18, one arm and one spring being located on one side of the shaft 7, and the other arm and the other spring being located on the other side of the shaft 7. It will, therefore, 50 be seen that, while the presser roller 24 may move toward and from the grinding roller 8 through a vertical plane extending through the axes of the rollers, as previously described, the presser roller 24 may also 55 move transversely to said plane or laterally of its axis against the cushioning action of one of the springs 29 for a purpose herein-after appearing.

The grinding rings and the presser roller 60 24 are inclosed above the base 4 and protected by a suitable sheet metal casing 28 which rests upon the base and is provided with slots or openings through which the shafts 7 and 23 extend.

65 One end of the shaft 7 extends outwardly

and is provided with a pulley 31 by means of which power may be applied to the machine. The shaft 23 may be driven instead of the shaft 7, or both shafts 7 and 23 may be driven.

The operation of the parts thus far described is as follows: Power is applied to the pulley 31 to rotate the shaft 7 and grinding roller 8 in the direction of the arrow in Fig. 1. The action of the roller 8 rotates the grinding rings 10, 11 and 12 in the same direction, due to the weight of the grinding rings and the pressure of the roller 24 which, during the operation of the machine, rotates about the axis of the shaft 23. During the actuation of the grinding roller and grinding rings, the material to be ground is introduced to one or both of the hoppers 16 and passes from the spouts 13, 14 and 15 and is deposited upon the lower portions of the inner faces of the grinding rings 10, 11 and 12, respectively. The material is then held against the inner faces of the grinding rings by centrifugal force and the material is thus carried by the rings during successive revolutions thereof. As the material thus carried by the grinding rings passes between the rollers 8 and 24 it is crushed or ground between the coacting faces of the grinding rings and the coacting faces of the inner ring 10 and the grinding roller 8. As the ground material accumulates upon the grinding rings it falls from the edges of an inner ring to an outer ring and is again ground therein and finally falls from the edges of the outermost ring 12 into the receptacle below.

During the grinding operation, the presser roller 24 may yield upwardly against the springs 25 and it may also yield laterally of its axis against one of the springs 29 as the material being ground passes between the rollers 8 and 24, thus insuring practically a constant and uniform crushing pressure or action between the grinding rings 110 and the innermost ring and the roller 8 at all times.

The spouts 14 and 15 may be dispensed with so that the material may be fed only to the innermost grinding ring thereby requiring all the material fed to the machine to be acted upon and ground by all the rings successively before finally falling from the edges of the outermost ring 12. Also, the rings 10, 11 and 12 may be made of uniform width so that the material will only be ground within the ring to which it is fed and will fall from the edges of each ring directly into the receptacle below.

Due to centrifugal force and the shape of the inner face of each grinding ring, there is a tendency for the material being ground to accumulate about the central portion of the inner face of each ring, and, therefore, in order to distribute the material

from the region of its accumulation I provide each ring with a pair of oppositely disposed plows 32, one extending into the ring from one side thereof and the other extending into the ring from the other side thereof. The outer end of each plow is secured to a short horizontal shaft 33 which is mounted in a bearing in a vertical wall 34 supported within the base 4. The outer end 10 of each shaft 33 has a horizontal lever 35 secured thereto. One end of each lever carries a weight which tends to turn the shaft 33 and move the nose of the plow 32 toward the inner face of its grinding ring, the movement of the plow being limited by the engagement of the other arm of its lever 35 with an adjustable screw 36 screwed into and through a lug projecting from the wall 34. By adjusting the screw 36 the interval 20 between the nose of its plow and the face of the grinding ring may be nicely regulated. Each plow 32 extends downwardly from its shaft 33 and rearwardly or in a direction against the direction of movement 25 of the grinding ring to a position about the central portion of the inner face of its grinding ring, and each plow is constructed and arranged to engage the material in the region of its accumulation and deflect it laterally toward the edge or side of the ring, the space between each plow and its grinding ring increasing as the plow recedes from its nose and the ground material passing under the plow and being distributed thereby over 30 the face of the grinding ring.

I claim:

1. In a grinding mill, the combination of a grinding roller, means for rotatably supporting the grinding roller, a grinding ring 40 surrounding and resting upon the top of the grinding roller, a presser roller engaging the top of the grinding ring, means for rotatably supporting the presser roller, the axis of one roller being movable toward and from the axis of the other roller, and a spring 45 pressing one roller toward the other roller.

2. In a grinding mill, the combination of a grinding roller, means for rotatably supporting the grinding roller, a grinding ring 50 surrounding and having its inner face engaged with the grinding roller, a presser roller engaging the outer face of the grinding ring, means for rotatably supporting the presser roller, one roller being movable toward and from the other roller and one roller being movable transversely to a plane 55 extending between the axes of said rollers, a spring pressing one roller toward the other roller, and a spring supporting one roller 60 against said transverse movement.

3. In a grinding mill, the combination of a grinding roller, means for rotatably supporting the grinding roller, a grinding ring surrounding and having its inner face engaged with the grinding roller, a presser 65

roller engaging the outer face of the grinding ring, a frame movable transversely to a plane extending between the axes of said rollers, a part carrying the presser roller and being carried by said frame and being movable toward the axis of rotation of the grinding roller, a spring supporting said frame against said transverse movement, and a spring pressing said part toward the axis of rotation of the grinding roller. 70

4. In a grinding mill, the combination of a grinding roller, means for rotatably supporting the grinding roller, a grinding ring surrounding and having its inner face engaged with the grinding roller, a presser roller engaging the outer face of the grinding ring, a pivoted frame movable on its pivot transversely to a plane extending between the axes of said rollers, a part carrying the presser roller and being carried by said frame and being movable toward the axis of rotation of the grinding roller, a spring supporting said frame against said transverse movement, and a spring pressing said part toward the axis of rotation of the 80 grinding roller. 85

5. In a grinding mill, the combination of a grinding roller, means for rotatably supporting the grinding roller, a grinding ring surrounding and having its inner face engaged with the grinding roller, a presser roller engaging the outer face of the grinding ring, a pivoted frame movable on its pivot transversely to a plane extending between the axes of said rollers, a part carrying the presser roller and being slidably connected to said frame and movable toward the axis of rotation of the grinding roller, a spring supporting said frame against said transverse movement, and a spring pressing said part toward the axis of rotation of the 90 95 grinding roller. 100

6. In a grinding mill, the combination of a shaft, a grinding roller carried by the shaft, a grinding ring surrounding and having its inner face engaged with the grinding roller, a presser roller engaging the outer face of the grinding ring, a collar surrounding said shaft, supporting means for said shaft and said collar, a frame projecting 110 from said collar, a part carrying the presser roller and being carried by said frame and being movable toward the axis of rotation of the grinding roller, a spring supporting said frame against movement about the axis 115 of said shaft, and a spring pressing said part toward the axis of rotation of the grinding roller. 120

7. In a grinding mill, the combination of a shaft, a grinding roller carried by the shaft, a grinding ring surrounding and having its inner face engaged with the grinding roller, a presser roller engaging the outer face of the grinding ring, a collar surrounding said shaft, supporting means for said 125 130

- shaft and said collar, a frame projecting from said collar, a part carrying the presser roller and being slidably connected to said frame and movable toward the axis of rotation of the grinding roller, a spring supporting said frame against movement about the axis of said shaft, and a spring pressing said part toward the axis of rotation of the grinding roller.
10. 8. In a grinding mill, the combination of a shaft, a grinding roller carried by the shaft, a grinding ring surrounding and having its inner face engaged with the grinding roller, a presser roller engaging the outer face of the grinding ring, a collar surrounding said shaft, a bearing surrounding said collar, a frame projecting from said collar, a part carrying the presser roller and being carried by said frame and being movable toward the axis of rotation of the grinding roller, a spring supporting said frame against movement about the axis of said shaft, and a spring pressing said part toward the axis of rotation of the grinding roller.
15. 9. In a grinding mill, the combination of a grinding roller, means for rotatably supporting the grinding roller, a grinding ring surrounding and having its inner face engaged with the grinding roller, a presser roller engaging the outer face of the grinding ring, a frame movable transversely to a plane extending between the axis of said rollers, a part carrying the presser roller and being carried by said frame and being movable toward the axis of rotation of the grinding roller, a spring supporting said frame against movement toward one side of said plane, a spring supporting said frame against movement toward the other side of said plane, and a spring pressing said part toward the axis of rotation of the grinding roller.
20. 10. In a grinding mill, the combination of a grinding roller, means for supporting the grinding roller, a grinding ring surrounding and having its inner face engaged with the grinding roller, a presser roller engaging the outer face of the grinding ring, a pivoted frame movable on its pivot transversely to a plane extending between the axes of said rollers, a part carrying the presser roller and being carried by said frame and being movable toward the axis of rotation of the grinding roller, a spring supporting said frame against movement toward one side of said plane, a spring supporting said frame against movement toward the other side of said plane, and a spring pressing said part toward the axis of rotation of the grinding roller.
25. 11. In a grinding mill, the combination of a grinding roller, means for rotatably supporting the grinding roller, a grinding ring surrounding and having its inner face engaged with the grinding roller, a presser roller engaging the outer face of the outer grinding ring, means for rotatably supporting the presser roller, and a spring pressing one roller toward the other roller.

gaged with the grinding roller, means to press the contacting faces of said roller and said ring together, and a plow adjacent the inner face of said ring and arranged to divert the material being ground laterally of the grinding face of the ring.

12. In a grinding mill, the combination of a grinding roller, means for rotatably supporting the grinding roller, a grinding ring surrounding and having its inner face engaged with the grinding roller, the interior diameter of the central portion of said ring being greater than the interior diameter of the side portions thereof, means to press the contacting faces of said roller and said ring together, and a plow adjacent the inner face of said ring and arranged to divert the material being ground laterally of the grinding face of the ring.

13. In a grinding mill, the combination of a grinding roller, means for rotatably supporting the grinding roller, a grinding ring surrounding and having its inner face engaged with the grinding roller, means to press the contacting faces of said roller and said ring together, a plow adjacent and movable toward and from the inner face of said ring and arranged to divert the material being ground laterally of the grinding face of the ring, means tending to move said plow toward said face, and means to limit the movement of the plow.

14. In a grinding mill, the combination of a grinding roller, means for rotatably supporting the grinding roller, a grinding ring surrounding and having its inner face engaged with the grinding roller, a grinding ring surrounding the first named ring and having its inner face engaged with the outer faces of the first named ring, and means to press the contacting faces of said roller and said rings together.

15. In a grinding mill, the combination of a grinding roller, means for rotatably supporting the grinding roller, a grinding ring surrounding and having its inner face engaged with the grinding roller, a grinding ring wider than and surrounding the first named ring and having its inner face engaged with the outer face of the first named ring, and means to press the contacting faces of said roller and said rings together.

16. In a grinding mill, the combination of a grinding roller, means for rotatably supporting the grinding roller, a grinding ring surrounding and having its inner face engaged with the grinding roller, a grinding ring surrounding the first named ring and having its inner face engaged with the outer face of the first named ring, a presser roller engaging the outer face of the outer grinding ring, means for rotatably supporting the presser roller, and a spring pressing one roller toward the other roller.

17. In a grinding mill, the combination of a grinding roller, means for rotatably supporting the grinding roller, a grinding ring surrounding and having its inner face engaged with the grinding roller, a grinding ring wider than and surrounding the first named ring and having its inner face engaged with the outer face of the first named ring, a presser roller engaging the outer face of the outer grinding ring, means for rotatably supporting the presser roller, and a spring pressing one roller toward the other roller.
18. In a grinding mill, the combination of a grinding roller, means for rotatably supporting the grinding roller, a grinding ring surrounding and having its inner face engaged with the grinding roller, a grinding ring wider than and surrounding the first named ring and having its inner face engaged with the outer face of the first named ring, the interior diameter of the central portion of the second named ring being greater than the interior diameter of the side portions thereof, and means to press the contacting faces of said roller and said rings together.
19. In a grinding mill, the combination of a grinding roller, means for rotatably supporting the grinding roller, a grinding ring surrounding and having its inner face engaged with the grinding roller, a grinding ring surrounding the first named ring and having its inner face engaged with the outer face of the first named ring, a presser roller engaging the outer face of the outer grinding ring, means for rotatably supporting the presser roller, one roller being movable toward and from the other roller and one roller being movable transversely to a plane extending between the axes of said rollers, a spring pressing one roller toward the other roller, and a spring supporting one roller against said transverse movement.
20. In a grinding mill, the combination of a grinding roller, means for rotatably supporting the grinding roller, a grinding ring surrounding and having its inner face engaged with the grinding roller, a grinding ring surrounding the first named ring and having its inner face engaged with the outer face of the first named ring, a presser roller engaging the outer face of the outer grinding ring, means for rotatably supporting the presser roller, one roller being movable toward and from the other roller and one roller being movable transversely to a plane extending between the axes of said rollers, a spring pressing one roller toward the other roller, and a spring supporting one roller against said transverse movement.
21. In a grinding mill, the combination of a grinding roller, means for rotatably supporting the grinding roller, a grinding ring surrounding and having its inner face engaged with the grinding roller, a grinding ring surrounding the first named ring and having its inner face engaged with the outer face of the first named ring, a presser roller engaging the outer face of the outer grinding ring, a frame movable transversely to a plane extending between the axes of said rollers, a part carrying the presser roller and being carried by said frame and being movable toward the axis of rotation of the grinding roller, a spring supporting said frame against said transverse movement, and a spring pressing said part toward the axis of rotation of the grinding roller.
22. In a grinding mill, the combination of two substantially vertically-arranged grinding rings, and means coöperating with said rings to grind material therein, one ring having an inner grinding face located below one edge of the other ring to receive material therefrom.
23. In a grinding mill, the combination of a grinding roller, means for rotatably supporting the grinding roller, a grinding ring surrounding and resting upon the top of the grinding roller, and a spring pressed rotatable means forcing the grinding ring down upon the grinding roller.

In testimony whereof I affix my signature in presence of two witnesses.

GEORGE S. EMERICK.
